UNITED STATES PATENT OFFICE.

WILLIAM J. BRADLEY, OF TROY, NEW YORK, ASSIGNOR TO THE RAIL JOINT COMPANY,
OF NEW YORK, N. Y., A CORPORATION OF NEW YORK.

PROCESS OF ROLLING RAIL-JOINT BARS.

1,277,287.

Specification of Letters Patent. Patented Aug. 27, 1918.

Application filed January 29, 1916. Serial No. 75,050.

To all whom it may concern:

Be it known that I, WILLIAM J. BRADLEY, a citizen of the United States, residing at Troy, in the county of Rensselaer and State 5 of New York, have invented certain new and useful Improvements in Processes of Rolling Rail-Joint Bars, of which the following is a specification.

This invention relates to the manufacture 10 of rail-joint bars of the type having a rail-supporting base-member which is provided at its inner edge with a reinforcement usually in the form of a rib.

The invention has for its object a simple 15 an economical process by means of which rail-joint bars of the character referred to can be successfully and commercially manufactured in the passes of a rolling mill. To this end the invention contemplates a process 20 of making a rail-joint bar with a reinforced base-member by a continuous operation, while at the same time shaping and so disposing the metal in the bar as it progresses through the various passes as to secure the 25 proportional distribution of metal to the best possible advantage without weakening the bar at any point. More specifically, the invention has in view a thoroughly practical and commercial process for manufacturing 30 the well-known continuous type of rail-joint bar whose base-member is provided with a rib or equivalent reinforcement, usually at its inner lower edge.

The process of the invention may be 35 carried out in different ways without departing from the spirit or principle thereof, but as a preferred example of progressively developing the metal shape in the passes of a rolling mill, a preferable and practical 40 means of employing the process is shown in the accompanying drawings, in which,—

Figure 1 is a sectional elevation of a set 45 of finishing rolls of a rolling mill having the several passes thereof specially designed for carrying out the present process.

Fig. 2 is an end view of the metal shape or bar as delivered from the initial or primary pass of the rolls.

Fig. 3 is a side elevation of the metal 50 shape or bar shown in Fig. 2.

Fig. 4 is an end view of the metal shape or bar illustrating the same as affected by an intermediate finishing pass of the finishing rolls.

Fig. 5 is a side elevation of the metal 55 shape or bar shown in Fig. 4.

Fig. 6 is an end view of the metal shape or bar as affected by the "leader" pass of the set of rolls.

Fig. 7 is a side elevation of the metal 60 shape shown in Fig. 6.

Fig. 8 is an end view of the metal shape or bar as delivered from the final pass of the set of rolls, showing the bar finished as 65 to size and shape.

Fig. 9 is a side elevation of the metal shape or bar shown in Fig. 8.

Fig. 10 is a side elevation of the bar section in the shape as delivered from the final 70 pass of the rolls, but illustrating the shearing step of the process which severs the bar into rail joint lengths; this view also indicating by dotted lines that step of the process wherein portions of the reinforcing rib 75 toward both ends of the joint are sheared off.

Fig. 11 is an end view showing by dotted 80 and full lines, respectively, the final step of the process which consists in bulldozing or bending the base-member into its final rail-setting position.

Fig. 12 is a side elevation of the rail-joint 85 bar entirely finished with the exception of the punching for bolt-holes which may be made before or after the severing of the bar into rail-joint lengths.

Similar letters of reference indicate similar parts in all the figures of the drawings.

In carrying forward the present invention the billet or bloom is preliminarily developed in the proper passes of the rolling mill until the bar reaches a form to be carried through the passes of the finishing rolls. The metal shape at this primary stage of the present process includes, in general outline and unfinished form, the splice-member *a*, the inclined foot-flange *b*, the base-member *c*, disposed at an angle to its final plane, and an enlarged rib or bulb *d* projecting to one side of the base-member *c*, from the inner edge portion of the latter. 90 This particular metal shape, containing a surplusage of metal at all points, is only of approximate form and size and is given this character in what may be termed the initial pass 1 of a set of finishing rolls *A*, *B* and *C*. 100

The walls of the initial pass 1 of the finishing rolls have the structural characteris- 105

ties of the metal shape shown in Figs. 2 and 3 of the drawings, and the walls of the next succeeding or intermediate pass 2 of the said rolls have the structural characteristics of the bar or shape shown in Fig. 4 of the drawings, whereby the several members *a*, *b*, *c*, and *d* thereof are reduced in thickness and shaped more nearly to the finished form thereof, with the base-member *c* still left in "open" position at a distance from its final plane. The next or leader pass 3 of the finishing rolls brings the metal shape still nearer to its final size and form by distributing the metal in such a manner as to substantially reduce the several members of the bar to very nearly the final proportional thickness thereof, although it will be observed that the leader pass of the finishing rolls still leaves the enlargement or rib *d* in an unfinished form. The said metal shape as delivered from the leader pass 3 of the finishing rolls is shown in Fig. 6 of the drawings and the shape as delivered from the final pass 4 of the rolls is shown in Fig. 8 of the drawings. The final pass 4 completes the distribution of metal in the bar and gives the final shape and size to the various parts, it being observed from the series of Figs. 2, 4, 6 and 8 that there is a gradual and progressive development of the rib *d* from the rather crude bulbous reinforcement of Fig. 2 into the relatively narrow and deep flange-like rib of Fig. 8, this final structural characteristic of said rib being produced by the shape of the pass walls of the final pass 4 of the rolls.

With the bar finished as to its shape and proportional distribution of metal, as shown in Fig. 8 of the drawings, the base-member *c* is still in its open position, displaced a distance from the final rail-seating plane thereof, and the next step in the process is to sever the bar into rail-joint lengths. That step of the process is illustrated by the view in Fig. 10 of the drawings and is preferably performed by shearing knives which can be utilized with the base-member *c* in the open position referred to. The rail-joint bar has now been finished except in two particulars: First, as to disposing the rib projection *d* along the central portion of the bar only, and, second, the "closing" of the base-member to its final position.

Accordingly, a further step in the process is the novel operation of eliminating the rib-projection along the opposite end portions of the bar, whereby a rib projection will be

left only along the central portion of the bar. This may be conveniently accomplished by shearing-off those portions of the rib which lie along both end portions of the bar, as indicated by the dotted lines in Fig. 10, with the result of leaving a centrally disposed rib projection as plainly shown in Fig. 12 of the drawings.

The shearing-off of end portions of the rib projection is preferably done with the base portion still in the "open" position, referred to, and when that step in the process has been completed the final operation is that of bulldozing or bending the base-member into its closed or final rail-seating and supporting position. This is shown by the full lines in Fig. 11 of the drawings, and the dotted lines in the latter figure, as well as in Fig. 12, indicate the position of the base-member and its reinforcement prior to the closing of the base-member.

As already indicated, it is to be understood that other means or instrumentalities may be employed to carry out the herein described process without departing from the spirit or principle of the invention, the herein described instrumentalities being simply used as an illustration of one method by which the process may be performed.

I claim,—

1. A process of making bars for rail joints which consists in subjecting a metal blank to a rolling operation producing a bar-shape having angularly disposed members one of which is formed at its edge with a continuous projection of metal, and subsequently removing sections of said projection of metal along points corresponding to the end portions of the finished rail joint length.

2. A process of making bars for rail joints which consists in subjecting a metal blank to a rolling operation producing a bar-shape having angularly related members one of which is formed at its edge with a continuous projection of metal, then severing the said bar shape into rail joint lengths, next removing portions of said projection of metal along opposite end portions of the bar, and subsequently displacing said member with its edge projection of metal into its final rail seating plane.

In testimony whereof I hereunto affix my signature in the presence of two witnesses.

WILLIAM J. BRADLEY. [L.S.]
